(57) **CLAIM**

The ornamental design for an ID bracelet, as shown and described.

DESCRIPTION

FIG. 1 is a top plan view of an ID bracelet showing our new design;

FIG. 2 is a bottom plan view thereof;

FIG. 3 is a side elevation view thereof;

FIG. 4 is an opposite side elevation view thereof; and,

FIG. 5 is a perspective view thereof.

The broken lines in the drawings, including the area within the broken lines of FIG. 2, illustrate portions of the ID bracelet that form no part of the claimed design. The other broken lines illustrating text and a QR code form no part of the claimed design.
